OVERHEAD ROOM DECORATION PANEL

John A. Zura, 6437 E. Sprague Road,
Independence, Ohio 44131

Filed Apr. 1, 1971, Ser. No. 130,561

Term of patent 14 years

Int. Cl. D25—02

U.S. Cl. D13—1

FIG. 1

FIG. 2

FIG. 3

FIG. 5

FIG. 1 is a perspective view from below showing an overhead room decoration panel embodying the invention;

FIG. 2 is an elevational view of the overhead room decoration panel of FIG. 1, taken on the line 2—2 of FIG. 4;

FIG. 3 is a sectional view taken on the line 3—3 of FIG. 4;

FIG. 4 is a side elevational view of the overhead room decoration panel of FIGS. 1, 2 and 3; and

FIG. 5 is a plan view from below taken on the line 5—5 of FIG. 4.

The dotted lines in FIGS. 2, 3 and 4 are for illustrative purposes only and form no part of the claimed design.

I claim:

The ornamental design for an overhead room decoration panel, as shown and described.
